DESIGN FOR A CABINET FOR AN AIR CONDITIONING UNIT OR SIMILAR ARTICLE

Edward W. Roessler, Schenectady, N. Y., assignor to General Electric Company, a corporation of New York

Application June 1, 1934, Serial No. 51,993

Term of patent 14 years

To all whom it may concern:

Be it known that I, EDWARD W. ROESSLER, a citizen of the United States, residing at Schenectady, in the county of Schenectady, State of New York, have invented a new, original, and ornamental Design for a Cabinet for an Air Conditioning Unit or Similar Article, of which the following is a specification, reference being had to the accompanying drawing, forming a part thereof.

The single figure of the drawing is a perspective view of a cabinet for an air conditioning unit or similar article embodying my new design.

I claim:

The ornamental design for a cabinet for an air conditioning unit or similar article substantially as shown.

In witness whereof, I have hereunto set my hand.

EDWARD W. ROESSLER.
